UNITED STATES PATENT OFFICE.

GEORGE RENNINGER, OF GLENSIDE, PENNSYLVANIA, ASSIGNOR TO PHILIP WUNDERLE, OF EDGEHILL, PENNSYLVANIA.

DESIGN FOR A BOX.

SPECIFICATION forming part of Design No. 34,785, dated July 16, 1901.

Application filed May 20, 1901. Serial No. 61,189. Term of patent 3½ years.

To all whom it may concern:

Be it known that I, GEORGE RENNINGER, a citizen of the United States, residing at Glen-side, in the county of Montgomery, State of Pennsylvania, have invented and produced a new and original Design for Boxes, of which the following is a specification, reference being had to the accompanying drawing, forming part thereof.

10 The figure represents a side elevation of a box embodying my design.

The leading feature of my design for a box is a cylindrical body simulating the body and sections of the cords of a drum and a removable lid simulating the top hoop of a drum and sections of cords matching those of the body at the bottom edge of the removable lid, the bottom hoop of the body having thereon representations of hooks and cords extending downwardly from the body and passing around said hooks.

In the drawing, A designates the body of the box, and B the lid thereof, both of cylindrical form.

On the sides of the body are the representations of a bottom hoop C and hooks D on said hoop. On the side of the body are the representations of sections of cords E, which extend from the bottom edge of the lid to the bottom hoop C and pass around the hooks D thereon. On said cords E are representations of slides F. On the side of the removable lid B are representations of hooks G and sections of cords H, which are represented as broken at the bottom edge of the lid. The tops of the broken sections of cords E and bottom of the broken sections of cords E' match, as at J. On the slides F are representations of stars K.

Having thus described my invention, what I claim as new, and desire to secure by Letters Patent, is—

The design for a box substantially as shown and described.

GEORGE RENNINGER.
